UNITED STATES PATENT OFFICE

103,064

DESIGN FOR A TEXTILE FABRIC

George Feinberg, New York, N. Y.

Application October 23, 1936, Serial No. 65,433

Term of patent 3½ years

To whom it may concern:

Be it known that I, George Feinberg, a citizen of the United States, residing in New York city, county and State of New York, have invented a new, original, and ornamental Design for a Textile Fabric, of which the following is a specification, reference being had to the accompanying drawing, forming part thereof, wherein—

The figure is a plan view of a textile fabric showing my new design, with a unit of design marked in dot and dash lines.

I claim:

The ornamental design for a textile fabric substantially as shown.

GEORGE FEINBERG.
